RICHARD McDOWELL, OF LAMBERTVILLE, NEW JERSEY.

CHECK-VALVE FOR STEAM-BOILERS.

SPECIFICATION forming part of Letters Patent No. 320,380, dated June 16, 1885.

Application filed August 7, 1884. (No model.)

To all whom it may concern:

Be it known that I, RICHARD McDOWELL, of Lambertville, in the county of Hunterdon and State of New Jersey, have invented a new 5 and useful Improvement in Check-Valves for Steam-Boilers, of which the following is a specification.

This invention relates to check-valves for steam-boilers, and it has for its object to provide a boiler with a check-valve, which is located on the inner side of the shell of the boiler in order to be thoroughly protected against the escape of steam in cases of collision or from any accidents that may occur to the feed-pipes. 10 Heretofore all check-valves have been placed on the outside of the boiler—that is, secured to the exterior side of the shell—and in cases of accident to the feed-pipes the valve-connection is broken at its weakest place, which is 15 the point at which its connection is made to the boiler. The valve thereby becomes separated from the boiler, leaving it without any check to the escape of steam, thus endangering the lives of those in the immediate vicinity.

It will be understood that my improved valve is applicable to any kind of boiler or steam-generator, but by preference I have illustrated the valve as attached to a locomotive or horizontal boiler.

In the accompanying drawings, which form part of this specification, Figure 1 represents a transverse vertical section through a portion of a locomotive-boiler, showing my improved check-valve as it appears when the flange B of the same is secured to the exterior side of the boiler-shell G. Fig. 2 represents a section similar to that of Fig. 1, illustrating my improved check-valve when its flange B is secured to the interior side of the boiler-shell G, also showing an outside check-valve, C, as it will appear when used in combination with my inside check-valve, which in some cases may be advisable, especially in high-pressure boilers. Fig. 3 also represents a section similar to Fig. 1, showing my improved valve with its flange B secured to the interior side of the boiler-shell G, and provided with an interior extension, i', of the feed-pipe i, so as to deliver the feed-water below the steam-space in any part of the boiler that may be desired.

The construction of my improved check-

valve is fully illustrated by the drawings, in which A represents a casting which is provided with a flange, B, and in which the valve-seat o is formed.

a represents a gate-valve, which is hinged to the casting by means of the hanger a' in such a manner as will admit of the valve being revolved on its seat when it is in position and without its being removed from the hanger. The valve a is provided on its under side with a socket, E, which is for the purpose of receiving or engaging with a tool, by means of which it can be properly ground and seated from the outside of the boiler without necessitating the removal of the valve or entering the boiler. The hanger a' is provided at its upper end with a tip, e, which is for the purpose of coming in contact with the flange B or boiler-shell G, and thereby preventing the valve from being thrown too far open. The casting A is provided with a suitable guard, as illustrated at D, which crosses the upper end of the hanger a' in such a manner as will prevent the hanger from becoming loose or disengaged from the casting should the rivet n become broken or useless.

It is my intention and preference that the flange B of the casting should be secured to the inside of the boiler-shell, as shown in Figs. 2 and 3, but it is not absolutely necessary so long as the valve-seat is inside of the circumferential line of the boiler-shell, or so long as the valve seat is inside of the point at which the connection is apt to be broken in case of accident to the feed-pipe. The flange B, therefore, being secured to the outside of the boiler-shell, as shown in Fig. 1, does not in the least respect reduce the safety and protection afforded by my valve, as in case of accident the feed-pipe would break at the point where it is joined to the casting A, thus leaving the valve perfectly intact.

The operation of my valve is the same as all other check valves—that is, the feed-water is forced by means of an injector or pump or any other suitable method through the feed-pipe i in the direction of the arrow. The force of the water will raise the valve, and thus pass into the boiler. When the force of water is stopped, the internal pressure will close the valve, and thus it remains until it again becomes necessary to feed the boiler.

It will be easily understood from a careful examination of the drawings that a strait-way valve similar to that shown at C, Fig. 2, could be used in place of the gate-valve, as described.

5 In fact, a check-valve of any practical construction can be used if located on the inside of the boiler, as described, and the results would be the same. I do not, therefore, confine myself to the use of any particular construction of valve, as it may be necessary to use valves of different constructions under different circumstances.

Having thus described my invention and its advantages, what I claim as new, and desire to secure by Letters Patent, is as follows:

- 15 1. A gate-check valve located on the inside of the boiler, in combination with a feed-pipe, *i*, and adapted to be operated by means of an injector or pumps in the manner specified.
- 20 2. A check-valve located on the inside of the boiler, in combination with an outside check-valve adapted to be operated in connection therewith by means of injector or pumps, as and for the purpose described.
- 25 3. A check-valve located on the inside of the boiler, and adapted to be operated as described in combination with the feed-pipe *i*, as specified, and for the purpose set forth.

4. A check-valve provided with a socket, *E*, or suitable projection formed to engage with a tool inserted from the outside of the boiler for the purpose of grinding and seating said valve, as described and specified.

5. A check-valve attached to the interior side of the boiler, constructed of a casting, *A*, as herein described, and provided with the guard *D*, for the purpose of holding the hanger *a'* in position should the bolt *n* become broken or detached, as set forth and specified.

6. A check-valve constructed as herein described, consisting of the casting *A*, provided with the flange *B*, guard *D*, and lip *d*, in combination with the hanger *a'* and valve *a*, provided with the socket *E*, for the purpose of grinding and seating said valve by means of a tool inserted from the outside of the boiler, all as and for the purpose herein specified and set forth.

In testimony that I claim the foregoing improvement in check-valves, as above described, I have herennto set my hand this 4th day of August, 1884.

RICHARD McDOWELL.
